UNITED STATES PATENT OFFICE.

EMILIE B. HANDEL, OF BALTIMORE, MARYLAND.

CONVERTIBLE BED.

Application filed December 3, 1920. Serial No. 429,129.

To all whom it may concern:

Be it known that I, EMILIE B. HANDEL, a citizen of the United States, residing at Baltimore and State of Maryland, have invented certain new and useful Improvements in Convertible Beds, of which the following is a specification.

This invention relates to a device for concealing beds or couches when not in use or preferably before the bed has been made up in the morning where the housewife has found it inconvenient at the time to attend to this particular duty, thereby preventing the bed from presenting an untidy or unsightly appearance, yet at all times subjected to ventilation and providing an extremely sanitary camouflaged bed, it being appreciated that the device may be employed at any time however.

The invention further relates to a bed covering particularly designed for use, although by no means limited, with the "four-poster" type of bed popular at this day, and to this end is designed so that the four posts may be removed with ease and the cover applied to the legs to entirely shield the bedding.

The invention is further designed to provide not only a bed covering, but also a convertible screen such as used in rooms where privacy is desired.

The invention is further designed in such a manner that the screen may be utilized as a seat or even a table, and to this end, I have provided one form of fabric for the cover frame of woven cane or reed which is not only substantial in construction but may also be finished to present a neat, attractive and novel appearance, especially for use on sleeping porches and the like.

Other objects will be evident upon reference to the following specification.

In the drawings—

Figure 1 is a perspective view, partly in section and illustrating the manner of application of my device to a bed or couch, and particularly a bed of the corner post style;

Figure 2 is an elevation of one end of the device, illustrating the manner in which the cover is fastened when in use as a screen;

Figure 3 is a sectional view on the line 3—3 of Fig. 2;

Figure 4 is a perspective view of the frame with the covering detached for the

purpose of showing the detail construction thereof;

Figure 5 is a detail of one of the corner constructions of one of the frame members, 60 and illustrating particularly the frame securing pin and its socket; and

Figure 6 illustrates a modified construction of my invention.

In many of the present day apartments 65 or living quarters, where often a bed room is utilized as a living room, it is desirous that the bed or couch when not in use, be concealed or otherwise covered so that its identity as a piece of sleeping furniture 70 be disguised or converted into a settee or the like. Further, it often happens that the housewife may find it necessary upon certain conditions to leave the making of the bed in the morning temporarily while 75 more urgent duties require her attention, in which case the bed is left in an untidy condition until an opportunity presents itself, possibly even late in the day, to remake the bed. Further, visitors may come 80 in before she has had an opportunity to make the bed.

It is with a view toward overcoming the unsightly appearance of the unkept bed that I have designed the invention by providing a device which may quickly and conveniently be placed over the bed and entirely covering the bed clothes, and even if necessary the bed frame so as to effectually disguise it or to all appearances, convert it into another piece of furniture and still have the advantage of free circulation 90 of air, thereby making it sanitary at all times.

In the drawings, I have shown the device as applied to what is known as the "four-corner post" bed, popularly in use at the present day, and comprising end and side frames 1 and 2 respectively, and legs 3. In the usual construction of the "four-post" bed, the legs 3 are continued upwardly above the upper plane of the mattress and covers to provide corner posts 4 which are integral therewith or at least not separable therefrom.

In the present construction, said corner posts are separable at their base 6 from the legs and are each provided with a dowel pin 7 which may be received in a correspondingly shaped recess 8 in the top of 110 said legs, permitting said posts to be readily removed when necessary so that the cover,

presently to be described may be placed in position over the bed.

The folding cover frame, shown more particularly in Figure 4, when in position over

5 the bed shown in Fig. 1, conforms substantially in size to the outside dimensions of the bed, being rectangular in form, and consisting of a main or central frame 9 to which is hinged at 10 upon each side, a folding wing
10 or frame 11, the outside corners 12 of which are provided with facial recesses 14 adapted to receive removable dowel pins 15 which cooperate respectively with the recesses 8 in the legs 3 of the bed when the frame is ex-
15 tended and in use as shown in Fig. 1.

The entire frame has a cloth covering 16 stretched thereover and secured by suitable fastening devices 18, the covering being continued beyond the frame members to pro-
20 vide curtains 19.

I have designed my device so that, when not in use as a bed covering, it may be employed as a screen often found in bedrooms where privacy is desired. For this purpose, 25 it is necessary that the curtains 19 be folded out of the way and as shown in Figure 2, this may be accomplished by providing said curtains at convenient positions with separable snap fasteners 20 preferably of the
30 glove type.

The sectional view in Figure 3 illustrates very clearly one method of folding and fastening the curtains, although I do not wish to limit myself in any manner to the specific
35 folding method which I have shown.

In Fig. 6 I have illustrated a modified form of my combined bed cover and screen, this embodiment of my invention comprising a main or central frame member 25 which is of
40 a size to completely cover the bed, said frame member 25 having hinged thereto at 26, lateral wings or frames 27, narrower than the central frame and designed to hang vertically over the side boards of the bed and
45 conceal them or at least the bed mattress and linen. The center frame is provided with facial recesses adjacent its corners to receive removable dowel pins 28 cooperating with the recesses 8 in the bed legs.

50 The frame members 25 and 27 have stretched thereon woven cane 30 and in the present embodiment of my invention, the device is designed when in use as a bed covering to be utilized also as a seat or table, the
55 frame and woven cane being of such substantial construction as will support the

weight of a lamp or other object or a person. As shown in Fig. 6, the cover may also be used as a screen, presenting a neat appearance.

60

As shown in Fig. 1, I have designed my invention such that the tops of the legs extend a sufficient distance above the upper plane of the bed mattress to support the cover frame in spaced relation thereto for 65 the purpose of providing a space permitting free circulation of air and maintaining the bedding in a sanitary condition.

It is considered of utmost importance to note that in this camouflaged bed herein disclosed and described, the spring and mattress may be readily removed for airing, unlike most concealed beds, which appear objectionable for sanitary reasons.

While I have particularly described the 75 elements best adapted to perform the functions set forth, it is obvious that various changes in form, proportion and in the minor details of construction may be resorted to, within the scope of the appended claims, 80 without departing from the spirit or sacrificing any of the principles of my invention.

Having thus described my invention, what I claim as new and desire to protect by Letters Patent is:

85

1. The combination of a bed having recessed legs, a cover frame having a fabric stretched thereover, and a pin arranged in each of the corners of said frame cooper-
90 ating with the recesses in said legs for detach-
ably supporting said frame over said bed.

2. In a bed covering, the combination of a bed, the legs of which are provided with recesses in their upper ends, a cover frame comprising a plurality of hinged folding 95 sections which when extended cover the body of the bed, a pin carried by each of the corners of the frame adapted to be detachably received by the recesses in said legs and a fabric stretched over each of said folding 100 sections.

3. A combined bed cover and screen comprising a folding frame, means for removably supporting it upon a bed frame, a fabric covering stretched over said folding 105 frame and having side and end curtains, and means for folding said curtains over said covering and detachably securing them thereto when the cover is used as a screen.

In testimony whereof I affix my signature.

110

EMILIE B. HANDEL.
